DESIGN FOR LEATHER

Samuel Shapiro, New York, N. Y.

Application September 3, 1935, Serial No. 58,408

Term of patent 3½ years

To all whom it may concern:

Be it known that I, Samuel Shapiro, a citizen of the United States, residing in New York city, in the county of New York and State of New York, have invented a new, original, and ornamental Design for Leather, of which the following is a specification, reference being had to the accompanying drawing, forming part thereof.

The figure is a plan view of a piece of leather showing my new design, the same constituting the design unit.

I claim:

The ornamental design for leather substantially as shown and described.

SAMUEL SHAPIRO.
